UNITED STATES PATENT OFFICE.

JOHN DAY NIX, OF NATCHEZ, MISSISSIPPI, ASSIGNOR OF ONE-THIRD TO LEWIS M. DALGRON,
OF NATCHEZ, MISSISSIPPI.

SMOKE-CONSUMER FOR BOILER-FURNACES.

No. 884,945.

Specification of Letters Patent. Patented April 14, 1908.

Application filed July 20, 1905, Serial No. 270,512. Renewed August 30, 1907. Serial No. 390,824.

To all whom it may concern:

Be it known that I, JOHN DAY NIX, a citizen of the United States, and a resident of Natchez, in the county of Adams and State of Mississippi, have invented a new and Improved Smoke-Consumer for Boiler-Furnaces, of which the following is a full, clear, and exact description.

In the combustion of fuel such as coal, for 10 the generation of heat and consequent evolution of steam in a suitable generator, it is well known that in the usual form for a furnace there results an imperfect assimilation of carbonaceous vapor liberated from 15 the burning fuel with oxygen from the atmosphere; furthermore, this want of proper association of the elements mentioned entails a positive and serious loss, as the particles of carbon driven off as smoke and permitted to escape, in many cases, represents 20 more than half of the heat-producing element of the fuel burned.

The object of my invention is to provide 25 novel details of construction for a smoke consumer, and its combination with the masonry "setting" for a steam boiler which will intimately mix waste carbon with oxygen from the surrounding air and subject it to sufficient heat for its proper association, 30 and under air pressure force the aero-carbonaceous mixture in the form of jets into portions of the fire-chamber of the steam generator for its combustion and conversion into heat for steam generation.

35 The invention consists in the novel construction, combination and arrangement of mechanical details, as is hereinafter fully described, and set forth in the appended claims.

Reference is to be had to the accompanying 40 drawings forming a part of this specification, in which similar characters of reference indicate corresponding parts in all the figures.

Figure 1 is a sectional side view of a steam boiler, of its "setting" and of the improvements combined with said masonry "setting;" Fig. 2 is a transverse sectional view of the construction shown in Fig. 1 taken substantially on the line 2—2 in said figure; Fig. 3 is an enlarged detached partly sectional side view of a carbonaceous liquid jet device employed; Fig. 4 is an enlarged detached transverse sectional view of a fan blower and a valve controlled inlet pipe for air, attached to the fan blower; and Fig. 5 is

an enlarged detached sectional side view of 55 damper mechanism employed.

The improvement is capable of effective co-operation with different styles of steam generators, but for illustration of its special construction and operation, it is represented in 60 the drawings as arranged in connection with the fuel combustion chamber and draft passages, for a horizontal tubular steam boiler and masonry "setting" therefor.

As appears in Figs. 1 and 2, 10 indicates a 65 horizontal tubular boiler that is of the well known return flue type, wherein the plurality of tubes or flues a extend from a flue sheet 10^a at the rear end of the boiler shell to the forward flue sheet 10^b, and are affixed at 70 their ends in spaced openings in said sheets in a water-tight manner, as usual. The boiler shell extends a proper length forward of the flue sheet 10^b and at the front end is closed by a front end wall 10^c affording a draft 75 chamber, 10^d, and on this extension of the shell a draft stack 10^e is mounted and secured over an opening therein, as shown in Fig. 1. The boiler is inclosed laterally and rearwardly by the masonry side walls 11 and 80 rear end wall 11^a, the usual angle plates 10^g that are projected from the boiler shell at opposite points thereon, seating upon offsets 11^b on the side walls, which latter afford support for the boiler and permit it to expand 85 and contract longitudinally, this being a well known provision in the "setting" of this class of steam boilers. The boiler is further supported by a front end wall 11^c of masonry, or, if preferred, of cast iron plates, this front 90 wall having a door 11^d therein below the boiler, and also an ash pit door 11^e below the door opening 11^d closing the usual opening not shown for removal of ashes from the ash pit 11^f.

95 A series of grate bars 12, and a plurality of differently constructed grate bars 12^a, extend from a bearing on the front wall 11^c rearwardly and rest on a bridge wall 13, these grate bars together divide the space forward 100 of the bridge wall into a fire chamber 11^g and an ash pit 11^h. The grate bars 12 are of ordinary form, each having a flat, perforated top wall and flanges at side edges thereof which depend an equal depth from the top 105 wall. Between the grate bars 12, the grate bars 12^a previously mentioned are positioned, said bars 12^a being hollow, closed at the front

ends, flat on their lower sides, and each provided with parallel side walls that merge at their upper edges in the lower edges of an inverted V-shaped top wall, as is clearly shown in Fig. 2, said wall having a row of perforations b in each inclined side thereof. A preferably rotary fan blower 14 is employed, which is positioned at a suitable point outside of the fire chamber of the boiler, and is adapted for a rotation of its wings 14^a, by power actuating the central shaft 14^b whereon the wings or fan blades are radially mounted, as is indicated in Fig. 4. The fan receives gaseous products of combustion from a conduit pipe 15 which extends from the center of the fan casing at one side thereof upwardly and then laterally into the stack 10^a, terminating in a flaring hood 15^a which depends within the stack near its base, for reception of products of combustion that enter the draft chamber 10^d, as will be herein-after more specifically described.

The bridge wall 13 is mounted upon a transverse foundation 13^a and consists of a metal box extending across the fire chamber at its rear end, the height of the bridge wall being so proportioned that the concaved upper side 13^b thereof is disposed at a proper distance below the shell of the boiler 10 and concentric therewith. In the upper side 13^b of the bridge wall, a series of spaced perforations c is formed that extend throughout its length, and in the rear side wall of the bridge 13, a similar series of perforations c' is formed near the top wall thereof, as appears in Fig. 1; furthermore, a set of perforations c' is formed in the front wall of the bridge 13 that are in registry with one in each grate bar 12^a at its rear end that is secured on the bridge wall.

From the discharge port of the fan 14, an air-conveying pipe 16 is extended into the ash pit 11^c and transversely thereof near its front end wall, this transverse extension 16^a of the air conductor pipe having a number of upright spaced branches d thereon, each connecting with the lower side of a respective hollow grate bar 12^a for transfer of air under pressure from the fan blower 14, into and through the hollow grate bars.

As shown in Fig. 1, a baffle plate 13^c is located longitudinally within the hollow bridge wall 13 which forms a partition which extends throughout the length of said bridge wall and at the upper edge is spaced from the top wall 13^b, thus permitting air forced into the bridge wall to escape through each set of perforations c , c' in about equal volume.

In the elbow 15^b that joins the conduit pipe 15 with the depending hood 15^a, a suitable opening e is formed, that is normally closed by means of a damper or grate 15^e which is hinged at its lower end upon the upper end of the hood, and at said hinge joint e a lever 15^e is secured which extends upward

at an angle when the grate or damper 15^e is closed, as shown by full lines in Figs. 1 and 5, the open position of the damper and lever appearing in dotted lines in Fig. 5. On the outer end of the lever 15^e, an adjusting rod 70 15^h is pivoted by one end, and thence extends down to a convenient point for manipulating at the front end of the boiler 10, the rod terminating in a handle, and also having a plurality of spaced teeth h projected from one 75 side toward the boiler head wall, on which is an angular bracket, an arm h' on which projects toward the teeth h . It will be seen that if the rod 15^e is drawn downward, and the arm h' is entered between or above certain of the teeth h , the rod will be held depressed and the damper gate 15^e opened correspondingly.

In the tubular conduit 15 near its junction with the inlet opening in the fan casing, a 85 valve 15ⁱ is introduced which, by its adjustment, controls the introduction of atmospheric air into the pipe, for admixture with the gaseous products of combustion that pass from the draft chamber 10^d through the 90 conduit pipe 15 and into the fan casing.

An oil feeding device is placed on the air conveying pipe 16, preferably near the fan 14, comprising a tank 17, from which extends a feed pipe 17^a in which is a feed graduating 95 valve 17^b, and from the latter projects downward and then horizontally a jet pipe 17^c which passes air-tight through the wall of the pipe 16, and extends longitudinally therein for the discharge of a fine jet of hydrocarbon 100 liquid toward the hollow grate bars 12^a.

As well known, the combustion of fuel evolves carbonic acid gas and other gaseous mixtures that are incombustible, and their accumulation in the retort like grate bars 12^a 105 and bridge wall 13, has a tendency if permitted, to obstruct the combustion of the other gaseous constituents, comprising oxygen, hydrogen and hydrocarbon vapor. To eliminate the waste gases as produced, I provide an escape pipe 18 controlled by the valve 18^a which at one end taps an end of the bridge wall 13, and thence is extended into the draft stack 10^a and is turned upwardly therein, as indicated in Fig. 1, the draft of the 115 stack serving to pull the noxious gases such as sulfur and carbonic acid gas, out of the hollow bridge wall and discharge the same into the surrounding air.

Rearwardly of the bridge wall 13, a combustion chamber 19, of ordinary form, is produced, the top wall 19^a of which inclines rearward and upward, thus forming a throat passage 19^b that converges toward its rear end and communicates at said end with an upright flue 10^c that is at 125 the rear end of the boiler 10, and affords a free passage for the products of combustion into the boiler flues a , and thence into the draft chamber 10^d. It may here be explained that for the perfect consumption of 130

the products of combustion that is effected by the improved apparatus, it is advantageous to combine a certain proportion of atmospheric air with said gaseous vapor which 5 may be destitute of oxygen essential for its perfect combustion. To this end, the air inlet valve 15^a before mentioned, is placed in the conduit pipe 15 for a graduated supply of air, that will be drawn thereinto and mixed 10 with the carbonaceous vapor as the air and gaseous compound are drawn into the fan 14 and thence forced through the pipe 16 by the fan. It is to be understood that the air inlet and valve controlling the same, may be placed 15 upon the pipes 15 or 16 at any selected point.

In operation, a fire is started in the chamber 11^a on the grate bars 12, 12^a, free draft being permitted through the hood 15^a into the stack 10^a, and also around said hood, the 20 grate 15^a being raised to open a free passage through the hood as is indicated by dotted lines in Fig. 5, and it will be obvious that as there are ample air passages in and between the grate bars 12, the natural draft of the 25 stack will effect a proper initial combustion of the fuel placed on the grate bars, but of course, a considerable volume of the valuable constituents of the fuel is lost in the form of unconsumed particles of carbon known as 30 smoke, and that is drawn out of the fire chamber and passes out of the stack.

To create a mechanical draft by use of the improved apparatus hereinbefore described, at a proper time the fan 14 is started to rotate, which will pull the air and waste products of combustion through the hood 15^a that has previously been closed by lowering its gate or damper 15^b, the supply of air and gases that are pervaded with carbon vapor 40 flow through the conduit pipe 15 into the fan 14. The supply of unburned carbon vapor and a moiety of associated air drawn by the fan through the valve 15^b into the fan is passed thence through the conveyer pipe 16 45 into the hollow grate bars 12^a, and as these bars have been highly heated by the combustion of fuel thereon, it will be obvious that the mixed air and carbonaceous vapor will become rarefied and highly heated, and the accumulating volume of air and gaseous vapor 50 will be forced out of the jet orifices b in the hollow grate bars, it being understood that this pressure of the gaseous mixture may be controlled by the speed of rotation given to 55 the fan 14. There may be, and preferably is, an admixture of hydrocarbon liquid in vaporized condition commingled with the products of combustion passed by the fan 14 into the grate bars 12^a. To this end, the 60 valve 17^b is opened a proper degree so as to permit a graduated amount of kerosene or other oil to drop into the pipe 16 and thence in combination with the other vapor, pass into the retorts or hollow grate bars 12^a, the 65 assimilation of the mixed vapors enriching

the gaseous fuel a degree proportioned to the quantity of oil thus fed into the grate bars. The fuel used in the usual manner in the fire chamber 11^a is supplemented in heating effect by means of the apparatus, as the pull of the fan 14 returns the larger amount of the unconsumed carbon or smoke into the fire chamber for combustion. 70

In further description of the operation, it will be noted that a certain volume of the gaseous mixture entering the hollow grate bars 12^a passes out of the perforations b in their upper sides, say one-third of said volume, the remaining two-thirds of the gaseous fuel passing into the bridge wall 13 through the orifices c^a at the rear ends of the grate bars 12^a. The perforations c and c^a, respectively formed in the top wall and rear side of the bridge wall, are collectively about equal in area with the perforations c^b and they permit an 80 escape of an equal quantity of the gaseous fuel from each series c and c^a for combustion along with the products evolved from burning fuel in the fire chamber. 85

The heat evolved from the perfect combustion of all consumable gaseous vapor thrown off from the burning fuel in the fire chamber by the improved smoke consumer, is greatly intensified thereby, and any of the waste carbon escaping from the fuel burning 90 on the grate bars 12, 12^a, will pass over the hollow bridge wall 13 into the combustion chamber 19 rearward thereof, thence through the throat 19^b, into the flue 19^c and thence forwardly into and through the flues a, accumulating in the forward chamber 10^d from which the fan 14 draws the products of combustion through the hood 15^a and pipe 15 into the body of said fan, from which it is expelled and conveyed through the pipe 16, 100 into the hollow grate bars 12^a, as before explained. 105

It will be apparent from the foregoing that the improvement when applied to a stationary boiler, as hereinbefore described, 110 will effect a complete combustion of the combustible gases evolved but not ordinarily consumed in the fire chamber of the boiler "setting", thus effecting a great saving and reduced consumption of fuel for the evolution of a given pressure of steam in the boiler, the operation being continuous and under perfect control. 115

Having described my invention, I claim as new and desire to secure by Letters Patent, — 120

1. A smoke consumer for furnaces, comprising a hollow bridge wall provided with perforations at the rear of the fire chamber, a hollow grate communicating with the bridge wall, and means for passing the gaseous products of combustion from the fire chamber through the grate into the bridge wall and thence through jet perforations in said bridge wall, for combustion while hot. 125

2. A smoke consumer for furnaces, com- 130

- prising a hollow bridge wall provided with perforations at the rear of the fire chamber, a plurality of hollow grate bars in the fire chamber and joining the bridge wall at their rear ends, and means for passing the gaseous products of combustion from the fire chamber through the grate bars into the bridge wall and thence out of jet perforations in said bridge wall, for combustion while hot.
- 10 3. A smoke consumer for furnaces, comprising a hollow bridge wall having jet perforations in its rear and top wall, said bridge wall being positioned at the rear end of the fire chamber, a plurality of hollow grate bars in open communication with the bridge wall at their rear ends, and means for receiving waste products of combustion from the draft passage of the furnace and passing said waste products through the hollow grate bars while they are hot, and thence through the hollow bridge wall to escape from the jet perforations for complete combustion.
4. A smoke consumer for furnaces, comprising a hollow bridge wall at the rear end of the furnace fire chamber, a plurality of hollow grate bars communicating at their rear ends with the front of the hollow bridge wall, said grate bars having perforations in their upper sides, and the bridge wall having perforations in its top wall and rear side, and means for receiving the waste products of combustion from the draft passage of the furnace and for mixing said waste products with air, and passing the mixed air and waste products through the grate bars, part of the gaseous fuel passing out of the perforations in the bars and the maximum portion into the bridge wall and thence through the perforations therein for complete combustion.
- 40 5. A smoke consumer for furnaces, comprising a hollow bridge wall at the rear end of the furnace fire chamber, said bridge wall having a series of perforations in its top wall and a series of perforations in its rear wall, and an upwardly disposed baffle plate therein, a series of hollow perforated grate bars communicating at their rear ends with the front of the bridge wall, and means for receiving the waste products of combustion from the draft passage of the furnace and for mixing said waste products with air, and passing the mixed air and waste carbonaceous vapor through the grate bars, part of the gaseous fuel passing out of the perforations in said bars and the maximum portion into the bridge wall and thence through the perforations therein for complete combustion.
6. A smoke consumer for furnaces, comprising a hollow bridge wall at the rear of the furnace fire chamber, said bridge wall having perforations therein, a plurality of hollow grate bars communicating at their rear ends with the hollow bridge wall, a fan, means adapting the fan to draw gaseous waste products from the draft passage of the furnace and pass said products into the grate bars and bridge wall under pressure, and means for introducing hydrocarbon fluid into the conveying means, for mixture with the waste products and for combustion therewith.
7. A smoke consumer for furnaces, comprising a hollow bridge wall at the rear of the furnace fire chamber, said bridge wall having two sets of perforations therein and an upright baffle plate for dividing the space in the bridge wall, a plurality of hollow grate bars communicating at their rear ends with the front of the bridge wall, a fan, means for adapting the fan to draw gaseous waste products from the draft passage of the furnace and pass said products into the grate bars and bridge wall under pressure, means for introducing hydrocarbon fluid into the conveying means, and means for introducing air thereinto, the pressure of the fan forcing the mixed waste product, hydrocarbon fluid and air into the grate bars and hollow bridge wall, that highly heat the gaseous fuel for combustion as it escapes from the perforations in the bridge wall.
8. The combination with a furnace fire chamber of a plurality of solid grate bars therein constructed to permit the passage of air therethrough, a plurality of hollow grate bars placed between the solid grate bars, a hollow bridge wall having perforations therein, the rear ends of the hollow grate bars having openings that lead into like openings in the hollow bridge, and means whereby to receive the products of combustion from the fire chamber, and to force the same through the grate bars and hollow bridge.
9. The combination with a furnace fire chamber, a plurality of solid grate bars therein constructed to permit the passage of air therethrough, a hollow bridge wall having perforations therein and located at the rear ends of the solid grate bars, and a plurality of hollow grate bars that communicate at their ends with the hollow bridge wall, of a fan adapted for suction and blowing, a hood hung in the draft passage of the furnace, a pipe connecting the inlet end of the fan with the hood, and a conveyer pipe connecting the outlet from the fan with the hollow grate bars.
10. The combination with a furnace fire chamber and a draft stack therefor, of a plurality of solid grate bars and interposed hollow grate bars forming the bottom of the fire chamber, a hollow bridge wall at the rear end of said fire chamber, having perforations therein, the rear ends of the hollow grate bars communicating with said bridge wall, a fan, a hood hung in the draft passage of the furnace, a conduit pipe extended from a hood and connecting with the inlet opening in the

fan, a valve in said conduit pipe for introduction of air, a conveyer pipe extended from the outlet end of the fan, and a hydrocarbon liquid supply both connected with the conveyer pipe, said pipe having a branch that is connected with the plurality of hollow grate bars.

In testimony whereof I have signed my name to this specification in the presence of two subscribing witnesses.
